UNITED STATES PATENT OFFICE.

HARRY B. STILZ, OF VALLEJO, CALIFORNIA.

OIL-BURNER.

1,066,161.

Specification of Letters Patent.

Patented July 1, 1913.

Application filed May 8, 1911. Serial No. 825,685.

To all whom it may concern:

Be it known that I, HARRY B. STILZ, a citizen of the United States, residing at Vallejo, county of Solano, State of California, have invented a certain new and useful Improvement in Oil-Burners, and declare the following to be a full, clear, and exact description of the same, such as will enable others skilled in the art to which it 5 pertains to make and use the same, reference being had to the accompanying drawings, which form a part of this specification.

My invention relates to improvements in oil burners in which the oil is atomized principally by mechanical means and has for its object to produce a burner which shall be simple in construction and reliable and efficient in operation.

In the burning of fuel oil, atomized in 20 passing through nozzles which spray it into a fine film by mechanical means, (effected usually by the centrifugal action of a rapidly rotating jet from a small circular orifice, causing the oil to leave the orifice as 25 an evenly spread mass over the surface of a cone), it has been found necessary, for obtaining the best results, to preheat the oil to such an extent that a portion of it will flash into vapor on encountering the lower 30 atmospheric pressure. With these burners some trouble has been experienced in starting the fire in a cold boiler without producing considerable smoke. In some cases it has been found that the kind of oil used for 35 fuel is not of the nature to be readily heated to a point where any of it will flash into vapor upon delivery from the nozzle. This is true of California fuel oil, especially that kind which is a by-product from the refineries and therefore has had nearly all of 40 its volatile constituents removed during the refining process and contains little more than the asphalt base. In order to secure perfect combustion with this variety of oil, 45 a suitably directed jet of steam is a valuable adjunct for securing perfect atomization; the steam which is introduced acting upon the oil in a manner similar to and producing results similar to those produced by the 50 vapor which flashes into existence with such oils as can be partially vaporized. Moreover, with those nozzles depending upon the centrifugal action of the jet alone, the delivery orifices must be very small, thereby 55 increasing the chances of choking up; a very high pressure must be maintained on the oil

supply system in order to prevent the formation of free oil vapor therein, the presence of which effectually destroys the atomization of the oil; and the steam heaters, together with other necessary auxiliary devices produce a rather complex system.

In accordance with my invention the steam is brought into action upon the oil in such a manner that the mechanical action of the jet is not interfered with, the two being so intimately associated that the oil may be effectually heated with even less steam than is required to pass through the steam heaters in the other system. I accomplish this by 65 the simple expedient of a readily accessible steam super-heating coil which prevents all possibility of destruction of atomization by reason of the oil becoming too hot. Consequently my invention may be regarded as 70 having for further objects the production of a burner which will efficiently burn any of the different kinds of fuel oil in commercial use and to reduce to a minimum the quantity of steam needed to assist in the atomization of the oil.

In all of the burners of which I am aware, a jet of flame is projected into the furnace at a high velocity, making it necessary to provide some sort of an abutment to check 85 and diffuse the flame, allowing little opportunity for the air to become mixed with the combustible, and producing an objectionable roaring noise. Further objects of my invention are to produce a burner which will 90 produce perfect combustion by insuring a perfect admixture of air with the fuel right at the zone of combustion; to utilize the velocity of the atomizing steam in such a manner that it will be dissipated in diffusing the oil into a spray which then enters the furnace at a relatively low velocity, obviating the objectionable noise of other 95 burners and permitting the furnace to become filled with flame without resorting to 100 special means for diverting and deflecting the flame after it enters the furnace.

It is sometimes desirable to make it possible to shut off the steam after a normal firing condition is reached and therefore, a 105 further object of my invention may be said to be the production of a burner which will permit the steam to be shut off and perfect combustion to be maintained thereafter.

The various features of novelty whereby 110 my invention is characterized will herein-after be pointed out with particularity in

the claims; but for a full understanding of my invention and of its various objects and advantages, reference may be had to the following detailed description taken in connection with the accompanying drawings, wherein:

Figure 1 is a longitudinal section through the burner end of a furnace equipped in accordance with one form of my invention, the burner being shown in side elevation; Fig. 2 is a section on line 2—2 of Fig. 1; Fig. 3 is a transverse section, on a larger scale, through the nozzle of the burner; Fig. 4 is a central longitudinal section through the nozzle.

Referring to Figs. 1 and 2 of the drawings, 1 represents a furnace of any usual or suitable construction having a front plate 2. Within the furnace, back of the front plate is a wall 3 of the fire brick or other refractory material. On the outside of the plate, and in front of the same is fitted a casing 4 having air ports 5. At the center of the casing, in the outer wall thereof, is a small opening 6 into which projects the nozzle 7 of my improved burner. A hole 8, co-axial with the hole in the front of the casing, but larger than the same, is cut through the front plate 2 and the wall 3. The nozzle injects a spray of oil or oil and steam through the openings 6 and 8 into the furnace. The opening 8 is made large enough so that it will not interfere with the incoming spray and yet small enough to bring the air which flows into the furnace through the ports 5 and the opening 8 into close contact with the atomized oil. When the nozzle is located at a suitable distance from the opening in the front of the furnace, (which opening is preferably circular,) it is possible to regulate the divergence of the spray so as to cause it completely to fill the opening or to pass through the opening in a stream having a smaller cross-sectional area than the opening. With lots of steam flowing, the flame is rendered relatively long and narrow. With the steam shut off and only pure oil flowing, the angle of divergence is not great unless the oil is under heavy pressure. By properly proportioning the amount of steam almost any degree of divergence may be obtained. After the burner has been in operation for a short time the refractory wall becomes so hot that it maintains an igniting temperature. Consequently, the fuel and the incoming air are brought together in a zone where combustion immediately begins, so that perfect combustion of the oil results and the furnace becomes filled with a slowly moving flame which spreads out on all sides as soon as the refractory wall is passed. In the arrangement shown, the oil, under pressure, is supplied to the nozzle through a pipe 9, while steam is admitted through a pipe 10. The steam may be under the normal boiler pressure and preferably passes through a

coil 11 which is placed on the inner side of the refractory wall and encircles the opening 8, before being admitted to the nozzle. This permits the steam to become highly superheated, this being advantageous not only in that it decreases the quantity of steam required but also because it decreases the quantity of moisture in the oil spray, and increases the temperature of the oil with the result that more perfect combustion results. Where the oil is heated in a suitable heater, as by the exhaust steam from the oil pump, the efficiency of the burner will be still further increased.

The nozzle may take various forms so long as it produces a whirling spray of atomized oil under all conditions which are encountered in practice. In Figs. 3 and 4 I have illustrated an arrangement in which both the steam and the oil are given rotary motions before they come in contact with each other. Referring to these figures, 12 represents a hollow plug having an inlet at one end for receiving the supply pipe 9. The other end is made conical as indicated at 13 and is provided with a restricted discharge outlet 14. Within the plug is fitted a spiral 15 which preferably has conical ends, as indicated at 16 in order that the incoming oil may be guided into the grooves of the spiral and will then leave the spiral in a thin conical layer. The oil is forced in under sufficient pressure to produce a high rate of rotation as it passes through the discharge orifice, thus causing the oil to spread out into a cone-shaped spray. The member 12 is screwed into or otherwise secured in a casing 17 which is provided with an annular groove 18 extending around the base of the cone-shaped end of the member 12. The casing extends somewhat beyond the discharge end of the plug and is there provided with an outlet 19 somewhat larger than the outlet 14. The casing is hollowed out so as to produce a shallow annular passage extending around the cone-shaped end of the plug from the passage 18 to the discharge outlet 19. The supply pipe for the steam opens into the casing tangentially to the passage 18, there being preferably a suitable nozzle 20 interposed between the supply pipe and the passage 18. Consequently when steam is introduced into the nozzle, it flows along the passage 18 and travels toward the discharge outlet in a thin whirling layer. The energy of the steam expanding through the member 20 is absorbed in setting up a violent rotation of the steam around the axis of the nozzle so that the rectilinear velocity of the jet from the orifice is relatively slow, corresponding about to the velocity of the air which enters the furnace, and thus affording the best opportunity for a perfect mixing of the jet with the air.

The operation is as follows: The oil leaves

the inner orifice of the nozzle in a conical spray and, before it can pass through the outer orifice, it is caught by the rotating steam and is perfectly atomized. In this condition the oil mixes with the requisite amount of air just as it reaches the hot refractory wall, and perfect combustion ensues.

It will be seen that the quantity of steam required for atomizing purposes is of course greatest when the fire is being started. With a strong draft and high furnace temperature once established, the supply of steam can be greatly reduced and in some conditions completely discontinued without detracting from the efficiency of combustion. In this case the mechanical atomization of the oil suffices. It will be understood that other gases than steam may be used for atomizing purposes, steam being usually most convenient because it is available without the use of pressure devices in addition to the boiler itself.

While I have illustrated a preferred form of my invention and have described this form with considerable particularity, I do not desire to be limited to the exact structural details thus illustrated and described, but intend to cover all forms and arrangements which come within the terms employed in the definitions of my invention constituting the appended claims.

I claim:

1. A nozzle having a small discharge orifice, means immediately adjacent to said orifice for producing a whirling motion in a liquid fluid passing therethrough, a casing surrounding said nozzle and having a restricted discharge port concentric with said orifice and means for causing a gaseous fluid passing through the space within said casing to enter said port in a whirling current.
2. A nozzle having a passage terminated by a small discharge orifice, a spiral within said passage covering the cross section thereof, a casing surrounding said nozzle and having a discharge port arranged concentric with and extending beyond said orifice means within said casing for whirling the fluid passing therethrough and connections for forcing a liquid through said nozzle and a gas through the space within said casing.
3. A nozzle having a passage terminated by a small delivery orifice for a liquid, a

spiral within said passage covering the cross section thereof, a casing surrounding said nozzle and having a restricted discharge port in line with said orifice and an admission port for a gaseous fluid directed therethrough, at an angle to the radii from the axis thereof.

4. A liquid spray nozzle having a passage terminated by a small discharge orifice, a spiral within said passage covering the cross section thereof, a casing surrounding said nozzle and having a restricted discharge port in line with said orifice, a conduit for a gaseous fluid directed tangentially into the annular space within said casing and an expanding nozzle positioned in said conduit.

5. A liquid spray nozzle having a passage abruptly contracted at one end by a cone shaped surface into a small delivery orifice, a transverse spiral within said passage and resting against the base of said cone shaped surface, a casing surrounding said nozzle and having a restricted discharge port in line with said orifice and means within said casing for whirling a gaseous fluid passing therethrough.

6. In combination, a furnace having an admission hole through its casing, a nozzle having means for projecting a hollow cone shaped film of oil from a round unobstructed delivery orifice into said furnace through said hole, means surrounding said nozzle for producing a whirling stream of gaseous fluid directed so as to penetrate said film of oil and means for supplying air into the furnace through said hole.

7. In combination, a furnace having an admission hole through its casing, a lining of refractory material for said hole, a nozzle having means for projecting a hollow cone shaped film of oil into said furnace through said hole, means surrounding said nozzle for producing a whirling stream of gaseous fluid directed so as to penetrate said film of oil, and means for supplying air into the furnace through said hole.

In testimony whereof, I sign this specification in the presence of two witnesses.

HARRY B. STILZ.
